SPROUTING BOX

Gary L. Davis, 736 East 650 South,
Centerville, Utah 84014

Filed Dec. 11, 1972, Ser. No. 313,808

Term of patent 14 years

Int. Cl. D11—02

U.S. Cl. D35—3 A

FIG 1

FIG. 1 is a perspective view of a sprouting box embodying my new design, taken from the front and slightly above and looking into the box;

FIG. 2, a front elevation view, the rear elevation view being identical thereto; and

FIG. 3, a top plan view.

I claim:

The ornamental design for a sprouting box, substantially as shown.
